Application October 15, 1931, Serial No. 568,947

15 Claims. (Cl. 270—50)

This invention relates to certain improvements in pin operating mechanism for use with the folding cylinders employed in connection with printing machines.

5 In a copending application of J. R. Tomlin, Serial No. 492,990, there is shown and described a folding mechanism in which an improved construction is provided for quickly shifting or changing the sheet taking pins and folding blades from collect to non-collect positions.

10 It is the especial object of the present invention to improve and simplify the mechanism shown in said application by which the sheet taking pins may be readily moved from collecting position to non-collecting position and vice versa.

15 It is a further object of the invention to produce a mechanism of few parts for effecting this change which can be operated from outside the cylinder.

20 With these and other objects not specifically referred to in view, the invention consists in certain novel parts, arrangements and combinations, which will be described in connection with the accompanying drawings and the novel features 25 pointed out in the claims hereunto appended.

In these drawings,—

25 Figure 1 is an end view of a folding and collecting cylinder, partly in section, showing the invention;

30 Figure 2 is a detail sectional view, on an enlarged scale, of the mechanism embodying the invention, the view being taken in the direction of arrow 2—3 of Figure 1, showing the non-collect position;

35 Figure 3 is a view similar to Figure 2 showing the parts in collect position;

40 Figure 4 is a detail view, partly broken away and partly in section, of part of the controlling mechanism, the view being taken on the opposite side of the machine from that shown in Figure 1 and in the direction of arrow 4 of Figure 5;

45 Figure 5 is a detail end view of the construction shown in Figure 4, looking in the direction of arrow 5 of that figure;

50 Figure 6 is a sectional view of the folding cylinder showing the sheet holding pins and the mechanism for operating the folding blades;

55 Figure 7 is a sectional view similar to Figure 3 and showing a portion of the means for silencing one of the folding blades; and

Figures 8, 9 and 10 are enlarged views showing detail parts of the mechanism for silencing one of the folding blades, as viewed in the direction of arrow 8, 9, 10 of Figure 6.

55 Referring now to these drawings, the invention

has been shown as embodied in a folding and collecting cylinder in which the collecting devices are in the form of pins, which are projected beyond the cylinder wall to take a sheet, or sheets, and rocked or retracted to release the sheet. 5 This cylinder is marked 1 in the drawings and is supported on suitable cylindrical bearing bushings 48a carried by eccentric bushings 48, which are mounted in any suitable framing 3, 4. In the particular mechanism shown, this collecting cylinder is what is known as a three part collecting cylinder and is provided with three sets of sheet taking pins, marked 5, 5' and 5'' in Figure 1, and these pins are carried on rock shafts 6 suitably mounted in the cylinder heads or ends 7, it 10 being understood that any desired number of pins may be used on each pin shaft, two such pins being indicated in Figure 2.

15 In accordance with the invention and in the machine shown, an improved mechanism is provided for operating the pin shafts so as to cause the pins to operate to take and release a sheet on each one-third revolution of the cylinder when not collecting, or to take and release three collected products on each two revolutions of the 20 cylinder when a product is to be collected, this mechanism being such that it can be operated from without the cylinder. That is, each set of pins acts to permit the folding off of a product at each revolution of the cylinder when not collecting or at each alternative revolution of the 25 cylinder when collecting.

30 While the specific mechanism employed may be somewhat varied, as shown, the rock shafts 6 have connected thereto cam rolls 8, 8' and 8'', 35 which are adapted to engage in a cam groove 9 of a cam 10, and the shafts 6 are normally biased to hold the sheet taking pins in impaling or sheet taking positions by any suitable means such, for example, as the springs employed in the co- 40 pending Tomlin application, Serial No. 492,990. This cam 10 is secured, as by bolts 11, to a swinging arm 12 pivoted on studs 13 secured in an annular member or ring 14. This ring is a two part ring, the parts being clamped together 45 by screw bolts 15, shown in Figure 1.

45 The annular member or ring 14 is secured to the frame of the machine so as to be fixed relatively to the cylinder in any suitable manner. In the best constructions, however, this connection will be an adjustable one so that the point at which the rolls 8, 8' and 8'' will engage the cam groove 9 may be varied, to vary the time of 50 operation of the sheet taking pins. The ring is therefore secured so as to be rotatable relatively 55

to the cylinder. As shown, it is secured to a boss 16 on the machine frame by bolts 17 working in slots 18 in the ring so that the ring may be given a small rotary adjusting movement. This is effected in the construction shown by right and left hand adjusting screws 19, 20, best shown in Figure 1, suitable lock-nuts 21 being provided to hold the parts in adjusted position. These screws work in a block 22 secured to the cap piece 220 by bolts 221. This block is slotted, as at 222, and receives a screw bolt 223 which engages with a projection or ear 224 on the ring, with which bolt the screws engage, so that when they are operated the ring is moved back and forth.

It will be understood from the description of the mechanism just given that when not collecting the cam rolls 8, 8', 8'' each engage the cam groove 9 on every revolution of the cylinder, so that three products are folded off at each revolution. When collecting, however, the swinging cam 10 is swung out of the way of each alternate roll and lets it pass by without engaging it, and thus each of the rock shafts will be operated once in each two revolutions, and the mechanism for operating the swinging cam and for shifting from non-collect to collect position will now be described.

Referring to Figures 2 to 4, the swinging cam 10 has depending therefrom an arm in which is secured one end of an actuator rod 23. This rod, at its other end, passes through a block 24 and is provided with a collar 25, between which and the block is a spring 26. Beyond the block, the end of the rod is hollowed, as shown at 27, to receive a short rod 28 on a hub 29, the rod 23 being secured to rod 28 in any suitable manner. This hub 29 is a swinging hub and carries a short shaft 30, shown in Figure 5, to which is secured a cam roll 31, the hub and associated parts being supported by a bracket 32 suitably secured to the frame 4 of the machine, before referred to.

This cam roll 31 engages a face cam 33 carried by one of the operating gears of the cylinder, marked 34, though it may be otherwise supported if desired.

It will be understood that the action of the spring rod 23 is to push the swinging cam 10 out of engagement with the cam rolls 8, 8', 8'', but that the movement of the cam roll 31 tends to pull it into the path of the rolls 8, the parts being so arranged and timed in the machine shown that this will occur so that three products are folded off at each two revolutions of the cylinder, this position being shown in Figure 3.

When now it is desired to operate the cylinder 1 so that three products are folded off at each revolution, that is, when no collecting is to be done, means are provided for swinging the cam 10 into position to engage the rolls 8, 8', 8'' at each revolution of the cylinder 1. While these means may be somewhat varied, there is provided an operating hand lever 35, the movement of which in one direction, silences the folding blade 36 and allows the cam roll 31 to operate the swinging cam 10 when it is desired to form collected products. As shown, this hand lever is pivoted on a hub 37 on a short shaft 38 supported in a bracket 39 suitably secured to the framing of the machine. This shaft is extended as shown in Figure 1, and has secured thereto a yoke arm 40 to which is connected an operating rod 41 which slides in a hub guide 42 on a bracket 43 secured to the frame of the machine. One end of

the shaft 38 is also carried by a hub 43' on the bracket 43.

It will be observed, referring to Figure 2, which shows the parts in non-collecting position, that when the lever arm 35 is moved outwardly, that is, to the position shown in Figure 2, the operating rod 41 is moved inwardly against the swinging cam 10 so that the cam is held in position to be engaged by the cam rolls 8, 8', 8'' at every revolution of the cylinder, so that three products are folded off the cylinder at every revolution.

As shown in Figures 6 and 7, the folding blades 36 and 36' are provided which act to fold the product into the bite of folding off rollers 44 and 45 in a well known manner. Two folding blades 36 and 36' and their mechanism are shown. Both of these blades operate when the cylinder is not collecting but only one of them operates when the cylinder is collecting, as will hereinafter be more fully described.

As shown in Figure 7, these folding blades are supported in blade holders 72, 73, which are rotatably mounted in ball bearings 74, supported on the ends of the frame 75 secured to a shaft 47. At one end, each of the blade holders is provided with a gear 76, and this gear is in mesh with an intermediate gear 77, supported on studs 78 on the frame 75, before referred to, this intermediate gear 77 in turn meshing with a gear 79, pinned at 80 to an eccentric bushing 48, as shown in Figure 6. It will be understood that the shaft 47 to which the frame 75 is secured is geared to a convenient driving shaft and the cylinder 1 is likewise driven, the gearing being so proportioned that the frame 75 makes one and a half revolutions for each revolution of the cylinder. As the cylinder 1 is rotated, the gears 77 travel around the gear 79 and drive the gears 76 to rotate the folding blades and causes them to fold products off to the folding rolls. It will be understood that with this construction, the folding blades are kept within the cylinder except at the time when they are to fold the product off into the bite of the folding rolls. For a straight run, both folding blades are driven, but for folding a collected product, one of them is silenced by a mechanism which is operable from outside the cylinder and which is fully disclosed in a pending application of John E. Tomlin, Serial No. 492,990 filed November 3, 1930. This mechanism operates in conjunction with the mechanism by which a change in the operation of the sheet taking pins is effected.

In the construction illustrated, the shaft 47 is hollowed out at one end to receive an actuating rod 81, this rod having a sliding movement in the shaft. The outer end of the shaft 47 has an interlocking collar 82, secured thereto and the rod 81 projects beyond the collar and carries an actuator head 83 at the end. This head, as shown in Figure 7, lies in a recess 84 in the control handle 35, which controls the operation of the swinging cam before referred to. The recess 84 of the operating handle has formed in its inner walls, a pair of ears 88, one of which is shown in Figure 7, the other ear being directly behind it on the opposite side of the rod 81. When the handle 35 is moved to the left, as shown in Figure 2, these ears engage the head 83 and pull the sliding rod outward. To force or move it inwardly or toward the right, as shown in Figure 7, the handle is provided with a cap 89 having a lug 90 which acts to force the rod inwardly into the shaft.

The operation of this handle 35 effects the change from the collect to the non-collect operation of the collecting cylinder without any sep- 75

parate adjustment being required in the mechanism for operating the pins or in the mechanism for operating the folding blades.

The push rod 81 is provided with a slot 91 which receives one end of a lever 92 pivoted at 93 in a yoke bracket 94 secured to the frame 15, before referred to. The other end 95 of this lever arm engages in a slot 96, in a rod 97 sliding in a bracket journal 98, also secured to the frame 15. The other end of this push rod 97 carries a forked lever 100. The lower end 101 of this forked lever engages a groove 102 of a clutch collar 103, slideable on the end of the folding blade shaft indicated by the numeral 104. This clutch engages a corresponding clutch member 105 forming a portion of the hub of one of the gears 16 which drives the shaft 104 carrying the folding blade 36.

To shift from a non-collect to a collect position, the operating handle 35 is shifted from the position shown in Figure 2 to the position shown in Figure 3. This movement of the handle, as best shown in Figure 7, operates the rod 81, which through the yoke lever 101 and its yoke 102 disengages the clutch and brings it into the position shown in Figure 10. This clutch being disengaged, gears 16 and 17 operate idly and the folding blade 36 is silenced so that its folding off function is stopped.

In the preferred construction, provision is made for locking the handle 35 so that it can be operated to change the mechanism from collecting to non-collect position or vice versa only when the parts are in the correct relative position to properly effect the change. The locking collar 82 is provided with a groove 109 with which a projection 110 on an extension 111 of the operating handle is adapted to engage. When the groove 109 and the projection 110 register, the handle may be moved from one position to the other, but with the groove in any other position, the handle is locked against movement. As shown in Figures 8 to 10, a spring rod 112 is provided having a rounded end 113 and working in a bracket 114, secured on a stud 115, on which the gear 17 is supported. The clutch member 103 is provided with a notch 116 with which this rounded end of the spring rod is adapted to engage. In the non-collect position, the spring rod is snapped outside of the clutch member, thus preventing any right hand endwise movement, as shown in Figure 8. In the position shown in Figure 10, the round end 113 of the rod 112 is snapped to the inner side of the clutch member 103 and a stop 117 now engages the notch 116, thus holding the folding blade in locked position for operating on a collect run. In Figure 9, the parts are shown in a transition position and it will be noted that the rounded end 113 engages with the clutch 116, thus positioning the shaft 104 and the parts carried thereby so the sliding clutch member will engage either the coacting clutch member 105 or the stop 117. With this construction, it will be seen that the shift from collect to non-collect position and vice versa may be made quickly from the outside of the machine. The handle 35 is locked in either collect or non-collect position, by means of a hand operated pin construction 118, this pin being engageable with holes 119, 120, formed in the arm and in a projection 121 in a bracket 39, before referred to, and thus the parts will be held locked in proper position during either collect or non-collect operation.

It will be understood that the collecting cylinder cooperates with means for feeding sheets or

a web thereto and, where a web is fed, with suitable cutting mechanism, these mechanisms not having been shown, as unnecessary for an understanding of the invention.

It will be seen with the construction shown and described that a very effective and simple means has been provided for shifting the parts from collect to non-collect position and vice versa, and while the invention has been shown and described in its preferred form it will be understood that certain changes and variations may be made in the particular construction shown and described without departing from the invention as defined in the claims hereunto annexed.

What is claimed is:

1. In a folding mechanism, the combination of a folding cylinder, sets of sheet taking pins carried thereby, means for operating a set of pins on alternate revolutions of the cylinder when collecting, a support fixed relatively to the cylinder, a swinging cam pivoted on the support, rolls cooperating with the cam, means for causing engagement of a roll and cam on each revolution of the cylinder when not collecting, and means for adjusting the support to adjust the position of the cam relatively to the cylinder.

2. In a folding mechanism, the combination of a folding cylinder, sheet taking pins carried thereby, an annular member fixed relatively to the cylinder, an arm pivoted in the member, a cam pivoted to the arm, a roll cooperating with the cam, means for swinging the cam from collect to non-collect position, and means for adjusting the annular member relatively to the cylinder.

3. In a folding mechanism, the combination of a folding cylinder, sheet taking pins carried thereby, a support fixed relatively to the cylinder, a cam pivoted on the support, rolls cooperating with the cam, a spring rod connected with the cam normally tending to hold it out of the path of the rolls, a second cam to which the rod is connected acting to cause the rod to move the pivoted cam into the path of a cam roll at alternate revolutions of the cylinder, a handle mounted for convenient manipulation outside the cylinder and a connection operated by the handle for swinging the cam so that it engages a cam roll at every revolution of the cylinder.

4. In a folding mechanism, the combination of a folding cylinder, three sets of sheet taking pins carried thereby, a cam for actuating the pins to fold off three collected products at each two revolutions of the cylinder when collecting, a swinging cam and cooperating cam rolls for folding off three products on each revolution of the cylinder when not collecting, means for shifting the cam from collect to non-collect position and vice versa, and means for shifting the position of the swinging cam relatively to the cylinder.

5. In a folding mechanism, the combination of a folding cylinder, sets of sheet taking pins operably supported thereby, means for operating the said pins, means operably connected with the said pin operating means for operating the pins for collect runs, and means operated by a handle located for convenient manipulation from a point outside the cylinder for locking the said pin operating means in position to positively operate the pins for non-collect runs.

6. In a folding mechanism, the combination of a folding cylinder, sets of sheet taking pins operably supported thereby, means for operating the said pins, means operably connected with the said pin operating means for operating the

- pins for collect runs, a handle mounted for convenient manipulation outside the cylinder, and means operably interposed between the handle and said pin operating means and operable by the handle to engage and lock the pin operating means in position to positively operate the pins for non-collect runs.
7. In a folding mechanism, the combination of a folding cylinder, sets of sheet taking pins operably supported thereby, a cam for operating the said pins, means operably connected with the cam for operating the pins for collect runs, a handle mounted for convenient manipulation outside the cylinder, and means operably interposed between the handle and said cam and operable by the handle to engage and lock the cam in a position to operate the pins for non-collect runs.
8. In a folding mechanism, the combination of a folding cylinder, sets of sheet taking pins operably supported thereby, means for operating the said pins, means operably connected with the said pin operating means for operating the pins for collect runs, a handle mounted for convenient manipulation outside the cylinder, and a movable member operably interposed between the handle and said pin operating means and movable by a movement of the handle to a position to engage and lock the said pin operating means in position to positively operate the pins for non-collect runs.
9. In a folding mechanism, the combination of a folding cylinder, sets of sheet taking pins operably supported thereby, means for operating the said pins, means operably connected with the said pin operating means for operating the pins for collect runs, folding blades, means for operating the folding blades for either collect or non-collect runs, and means located for convenient manipulation outside the cylinder for controlling the folding blade operating means and for locking the said pin operating means in position to positively operate the pins for non-collect runs.
10. In a folding mechanism, the combination of a folding cylinder, sets of sheet taking pins, means for operably supporting the said pins, a movable cam for operating the said pin supporting means and pins, means operated by movement of the folding mechanism and operably connected with the movable cam for moving the cam in position to engage the said pin operating means and positively operate the pins for collect runs, and a handle located for convenient manipulation from a point outside the folding cylinder and operably connected with the movable cam for locking the cam in position to engage the said pin supporting means and operate the pins for non-collect runs.
11. In a folding mechanism, the combination of a folding cylinder, sets of sheet taking pins carried thereby, a support fixed relative to the cylinder, a cam pivoted on the support, rolls cooperat-
- ing with the cam, a lever and connections operated thereby for swinging the cam so that it may be engaged by a roll on alternate revolutions of the folding cylinder, a handle mounted for convenient manipulation outside the cylinder, and means operable by the handle for locking the cam in position to engage the roll on every revolution of the folding cylinder.
12. In a folding mechanism, the combination of a folding cylinder, sets of sheet taking pins, means for operably supporting the said pins, folding blades, means for operating the folding blades for either collect or non-collect runs, a movable cam for operating the said pin supporting means and pins, means operated by a movement of the folding mechanism and operably connected with the movable cam for moving the cam to a position to engage the said pin supporting means and positively operate the sheet taking pins for collect runs, and common means located for convenient manipulation from a point outside the folding cylinder for controlling the folding blade operating means and for locking the movable cam in position to engage the pin supporting means to operate the pins for non-collect runs.
13. In a folding mechanism, a folding cylinder, sets of sheet taking pins operably supported thereby, means for operating said pins, means operably connected with the said pin operating means to cause the pin operating means to operate the pins for collect runs, a handle mounted for convenient manipulation outside the cylinder, and means operably interposed between the handle and the said pin operating means and operable by the handle to engage and lock the pin operating means in position to positively operate the pin for non-collect runs.
14. In a folding mechanism, the combination of a folding cylinder, sets of sheet taking pins operably supported thereby, means for operating the said pins, means operably connected with the said pin operating means for operating the pins for collect runs, and means located for convenient manipulation outside the cylinder for locking the said pin operating means in position to positively operate the pins for non-collect runs.
15. In a folding mechanism, the combination of a folding cylinder, sets of sheet taking pins, means for operably supporting the said pins, a movable cam for operating the said pin supporting means and pins, means operated by a movement of the folding mechanism and operably connected with the movable cam for moving the cam to a position to engage the said pin supporting means and positively operate the sheet taking pins for collect runs, and means located for convenient manipulation from a point outside the folding cylinder for locking the movable cam in position to engage the pin supporting means to operate the pins for non-collect runs.

JAMES D. SPILLANE.
